[57] CLAIM

The ornamental design for a fuel tank inlet location indicator, as shown and described.

DESCRIPTION

FIG. 1 is a front elevational exploded view of the fuel tank inlet location indicator of the present invention;

FIG. 2 is a back elevational exploded view of the fuel tank inlet location indicator of FIG. 1;

FIG. 3 is a left side elevational exploded view of the fuel tank inlet location indicator of FIG. 1;

FIG. 4 is a right side elevational exploded view of the fuel tank inlet location indicator of FIG. 1;

FIG. 5 is a top plan exploded view of the fuel tank inlet location indicator of FIG. 1;

FIG. 6 is a bottom plan exploded view of the fuel tank inlet location indicator of FIG. 1; and,

FIG. 7 is a front elevational view of the fuel tank inlet location inicator of FIG. 1.

The broken lines showing alternate locations in FIG. 7 are for illustrative purposes only and form no part of the claimed design.
